E. L. WILLIAMS.

BLADE SHARPENER.

APPLICATION FILED AUG. 31, 1914.

1,131,450.

Patented Mar. 9, 1915

UNITED STATES PATENT OFFICE.

EDWARD L. WILLIAMS, OF SANTA CRUZ, CALIFORNIA, ASSIGNOR TO EGITE MANUFACTURING COMPANY, OF SANTA CRUZ, CALIFORNIA, A CORPORATION OF CALIFORNIA.

BLADE-SHARPENER.

1,131,450.

Specification of Letters Patent.

Patented Mar. 9, 1915.

Application filed August 31, 1914. Serial No. 859,583.

To all whom it may concern:

Be it known that I, EDWARD L. WILLIAMS, a citizen of the United States, residing at Santa Cruz, in the county of Santa Cruz and State of California, have invented certain new and useful Improvements in Blade-Sharpener, of which the following is a specification.

This invention relates to devices for sharpening blades, and has reference more particularly to a new and improved device for effecting the sharpening of the blades of safety razors and similar edged tools.

The main object of the invention is to provide an improved and simplified device for sharpening safety razor blades and like tools in an easy and expeditious manner and without requiring any special skill on the part of the user.

Another object of the invention is to provide a device wherein the sharpening effect will be even and uniform throughout the cutting edge, independently of any skill and care in the manipulation of the device on the part of the user.

These and other objects and advantages are attained by the invention, an approved mechanical embodiment of which is illustrated in the accompanying drawing, where-

in—

Figure 1 is a perspective elevation of the complete device; Fig. 2 is a vertical cross section, partly in elevation, through the hone block and its supporting frame and the blade holder; Fig. 3 is a fragmentary top plan view, partly in horizontal section, of the hone block, frame and blade holder; Fig. 4 is a fragmentary top plan view of one end portion of the hone block and its supporting frame, and Fig. 5 is an edge elevation of the hone block and its supporting frame.

Referring to the drawing, 10 designates as an entirety a hollow rectangular supporting frame that is provided at its four corners and on both sides with supporting legs 11, the ends of which latter are preferably tipped with rubber pads 12 or similar material to avoid scratching and marring of the supporting surface of the frame.

Rigidly supported within the rectangular frame 10 is a hone block 13 of suitable abrasive material, to one side of which is preferably secured a stropping pad 14 of

leather. To rigidly support the hone block, the margins of the longitudinal side bars of the frame are bent or crimped inwardly over the longitudinal edges of the hone block 13, as clearly shown at 10' in Fig. 2; the working surfaces of the block 13 and stropping pad 14 (where the latter is employed) projecting safely above or beyond the inturned margins 10' of the supporting frame. Secured to or formed integral with the longitudinal side bars of the frame are a pair of trackways 15 that are depressed below the plane of the working surface of the sharpening element. Coöperating with the structure thus far described is a blade holder. This latter, in the broad aspect of the invention, comprises a rod or spindle having means for clamping a razor blade, anti-friction rollers freely rotatable on the spindle adapted to engage the trackways of the supporting frame of the sharpening element, and hand-grip extensions adapted to be grasped, one by each hand of the operator, whereby the blade may be traversed back and forth over the sharpening element with varying pressure thereon. The blade holder, in the construction herein illustrated, comprises the following parts.

16 designates a flat intermediate blade supporting member on which may be formed centering studs 17 adapted to co-operate with the holes usually formed in safety razor blades, one of which, of the double edge variety, is shown at 18. At one end the blade supporting plate 16 is rigidly secured by a threaded end portion 19 to a handle member 20. The opposite end of the blade supporting plate 16 also has a threaded connection with the reduced inner portion 21 of an arbor 22, on which latter is slidably mounted a tubular handle member 23. The arbor 22 terminates at its outer end in a head 24, and the arbor 22 is normally forced outwardly of the tubular handle member 23 by a coiled spring 25 confined between annular shoulders 26 and 27 on the arbor 22 and tubular handle member 23, respectively.

The inner ends of the handle members 20 and 23 are turned down to form journal bearings 28 and 29 for a pair of wheels 30 that are adapted to travel over the trackways 15 of the hone supporting frame, said

wheels being guided laterally by the vertical portions of the longitudinal side frame members on which the trackways are formed, so as to prevent any substantial canting or skewing of the blade holder during its reciprocating movements. The wheels 30 may be confined on their bearings by slightly upsetting the outer ends of the latter, or in any other suitable manner.

10 The blade 18, when mounted on the support 16, is securely gripped thereon by a spring clamp 31, which latter is preferably hinged at 32 to one end of the blade supports 16, just inwardly of the wheel 30,

15 while its opposite end is formed with a projecting tongue 33 that, when the spring clamp is pressed down flat upon the blade 18, lies within a shallow groove or recess 34 formed in the opposite threaded end or 20 shank of the blade support 16; this tongue 33 being normally confined in said groove by the inner reduced end of the tubular handle member 23, such engagement being normally maintained by the spring 25. Where 25 the blade support 16 is provided with the centering studs 17, the spring clamp 31 will also be provided with registering holes 31' to coöperate with said studs. To prevent relative turning movement be- 30 tween the blade support 16 and the handle member 23, said parts are formed with a groove and key connection indicated at 35 in Fig. 2 that permits relative longitudinal movement but prevents relative turning 35 movement.

The use of the device will be readily apparent from the foregoing description. The spring clamp 31 being in the released position indicated by dotted lines in Fig. 2, the 40 blade 18 is placed on the supporting plate 16, the tubular handle member 23 is retracted over the arbor 22 so as to expose the groove 34, into which the tongue 33 of the spring clamp 31 is then pressed and the 45 handle member 23 is then allowed to slide inwardly over the same, confining it in place. The blade holder having been positioned on the hone with the wheels 30 in engagement with the trackways 15, by means 50 of the handles 20 and 23 the entire blade holder is reciprocated lengthwise of the surface of the hone, being oscillated at the end of each stroke to bring the edges alternately into engagement with the surface of the 55 hone. Where the blade requires both honing and stropping it is, of course, first roughly sharpened on the honing surface of the block 18, after which, by simply inverting the frame and block, the blade can be finished by a similar operation on the stropping surface 14. To remove the sharpened 60 blade, it is necessary only with the thumb and fingers to produce a relative inward movement between the head 24 of the arbor 65 22 and the outer end of the tubular handle

member 23, whereupon the spring clamp 31, being released, springs upwardly out of engagement with the razor blade, and the latter may then be removed.

It will be manifest to those skilled in the art that the device shown and described may be modified in minor particulars without departing from the essential principles of construction involved and without sacrificing any of the advantages inhering in the invention. Hence, the latter is not to be understood as limited to the exact and specific structural details shown and described.

I claim:

1. A stropping or honing device for safety razor blades, consisting of a rod or spindle having means for clamping a razor blade, anti-friction rollers freely rotatable on the spindle adapted to engage a suitable track-frame for a sharpening element, and hand-grip extensions adapted to be grasped one by each hand of the operator, whereby the blade may be traversed back and forth over the sharpening element with variable pressure thereon.

2. A stropping or honing device for safety razor blades, consisting of a rod or spindle having a movable clamping jaw, anti-friction rollers freely rotatable on the spindle adapted to engage a suitable track frame for a sharpening element, and hand-grip extensions adapted to be grasped one by each hand of the operator, whereby the blade may be traversed back and forth over the sharpening element with variable pressure thereon, one of said hand-grip extensions being mounted for endwise movement to engage and release said clamping jaw.

3. In a blade-sharpener, the combination of a block of abrasive material, a frame in which said block is rigidly mounted, said frame being provided with laterally projecting trackways extending lengthwise of two opposite sides thereof, and said trackways being depressed below the plane of the upper surface of said block, a blade-carrier, a pair of rollers journaled on said blade-carrier and removably engaging said trackways and serving to both guide and support said blade-carrier relatively to the upper surface of said block, and a pair of handle members non-rotatably connected to the ends of said blade-carrier and projecting laterally beyond said trackways in position to be grasped by the user whereby the blade-carrier may be moved back and forth upon, and tilted and reversed relatively to, said trackways.

4. In a blade sharpener, the combination of a rectangular frame provided with trackways on two of its opposite sides, a block of abrasive material rigidly mounted within and carried by said frame, a blade-carrier, a pair of rollers rotatably mounted on said blade-carrier, said rollers being adapt-

ed to removably engage and travel along said tracks and support and guide said blade-carrier above said block, and a pair of handle members non-rotatably attached to said blade-carrier so as to project lengthwise of the latter beyond said trackways, one of said handle members being movable

lengthwise with respect to the blade-carrier to lock a blade in position in said blade-carrier.

EDWARD L. WILLIAMS.
